UNITED STATES PATENT OFFICE.

JAMES C. KARNES, OF BUFFALO, NEW YORK.

MEANS FOR AUTOMATICALLY FIRING A PROJECTILE.

Application filed July 14, 1925. Serial No. 43,568.

(GRANTED UNDER THE ACT OF MARCH 3, 1883; 22 STAT. L. 625.)

To all whom it may concern:

Be it known that I, JAMES C. KARNES, a citizen of the United States, and a resident of Buffalo, county of Erie, and State of New York, have invented an Improvement in Means for Automatically Firing a Projectile, of which the following is a specification.

The invention described herein may be used by the Government, or any of its officers or employees in prosecution of work for the Government, or by any other person in the United States, without payment to me of any royalty thereon, in accordance with the act of March 3, 1883.

This invention relates to means for automatically firing a projectile on setting the fuse thereof within a gun.

In firing at rapidly moving aerial targets, it is necessary in order to insure a reasonable degree of accuracy that the "dead time of maneuver" be reduced to a minimum.

Accordingly, I have shown in a previous application, Serial Number 20,537, filed April 3, 1925, a mechanism for setting a fuse

after the round is spaced within the gun. This is accomplished by providing an index scale wheel positionable angular amounts proportionate to fuse range and adapted to limit movement of a setting wheel connected through the gun to a fuse.

In order to effect a further reduction in the "dead time" and to eliminate the duties of the gun firer it is contemplated in the present invention to electrically connect the primer of the round with the engaging elements of the fuse setter mechanism so that the fuse may be set and the gun fired simultaneously with one operation.

The mechanism for setting the fuse within the gun will be but briefly described as it is specifically covered in a separate application.

To these and other ends, my invention consists in the construction, arrangement, and combination of elements, described hereinafter and pointed out in the claims forming a part of this specification.

A practical embodiment of the invention is illustrated in the accompanying drawings, wherein,

Fig. 1 is a longitudinal sectional view

through the breech end of a gun equipped with my improved fuse setting and firing apparatus;

Fig. 2 is an enlarged sectional view of the actuating mechanism;

Figs. 3 and 4 are views in side elevation of Fig. 2 showing the setting gear respectively in inoperative and operative position;

Fig. 5 is a detail view of the inner worm wheel;

Fig. 6 is a detail view of one of the contacts; and

Fig. 7 is a diagrammatic view showing the electric wiring.

Referring to the drawings by numerals of reference:

The fuse setting apparatus consists essentially of an actuating mechanism 5 mounted exteriorly of a gun 6 and operatively connected with a specially designed round of ammunition 7, the projectile of which is equipped with a time fuse 8 of any suitable type including a positioning element.

Rotatably mounted in the base of the cartridge case is a bevel gear 9 having an electric firing primer 10 and the gear is connected to a rod 11 extending axially of the case and removably keyed in the positioning element of the fuse 8. The flame from the primer is conducted through a passage 12 and vent holes 13 in the rear end of the rod to the propellant charge in the cartridge case.

Passing through the breech ring 6^a of the barrel is a shaft 14 on the ends of which are fixed respectively within and exteriorly of the barrel a bevel pinion 15 and a spur pinion 16. The pinion 15 is disposed in a recess of the breech block 17 and is normally disengaged from the bevel gear 9 by means of the spring 14' to permit loading of the round and extraction of the empty case.

The actuating mechanism of the fuse setter consists of a setting gear wheel 18, mounted exteriorly of the barrel and meshing with the spur pinion 16, and a concentric index worm wheel 19 provided marginally with a scale 20 graduated in values of fuse range and movable through a self-locking worm 21 mounted in a casing 22 on which is inscribed an index line 23. The setting wheel 18 and the index wheel 19 are provided with

engaging stop members 18^a and 19^a, each having an insulated contact 18^b and 19^b, the lead wire of one being grounded and the other lead wire connected to an insulated pin 24 in the breech block which contacts with the primer when the breech block is closed.

When the mechanism is in a position of rest at maximum range the stop 19^a on the 10 worm wheel rests against the zero stop 25 on the casing 22 while the stop 18^a on the countermovable setting wheel is brought up against the opposite side of the zero stop when the gear is restored to its normal position by a torsion spring 26.

In operation, when the index worm wheel has been moved either manually or automatically an amount proportionate to the required fuse range as indicated on the range 20 scale, the contact 19^b assumes the correct circumferential position with relation to the zero stop 25. The shaft 14 is then moved inwardly until the pinion 15 meshes with the gear 9 of the cartridge whereupon the setting 25 wheel is rotated until its contact 18^b engages the contact 19^b thereby completing the circuit and firing the primer. At the instant that the contacts meet, the fuse has been correctly set according to the required fuse 30 range as registered on the range scale by the index line 23. Consequently, the fuse is set and the gun fired simultaneously with one operation.

While in the foregoing there has been illustrated and described, such combination and arrangement of elements as constitute the preferred embodiment of my invention, it is nevertheless desired to emphasize the fact that interpretation of the invention should 40 only be conclusive when made in the light of the subjoined claims.

I claim:

1. Means for automatically firing a round of ammunition on setting the fuse thereof, embodying a pair of rotatable fuse setting 45 members each provided with a contact, one of said members adapted to limit movement of the other and the meeting of the contacts determining the setting of the fuse of a projectile and closing an electrical circuit to 50 fire the primer of the round.

2. Means for automatically firing a round of ammunition on setting the fuse thereof, embodying a pair of rotatable fuse setting members each provided with a contact, and 55 the meeting of the contacts determining the setting of the fuse of a projectile and closing an electrical circuit to fire the primer of the round.

3. Means for automatically firing a round 60 of ammunition on setting the fuse thereof, embodying a pair of fuse setting members each provided with a contact, and the meeting of the contacts determining the setting of the fuse of a projectile and closing a cir- 65 circuit to fire the primer of the round.

4. The combination with a round of ammunition having an electric primer, of means for setting the fuse of said round within a gun, and electrical connections with the setting means for simultaneously firing the primer when the fuse has been set.

5. A gun and mechanism on the gun adapted to set the fuse of a round loaded in the gun and to close an electrical circuit to 75 fire the primer of said round.

6. A device including means for setting the fuse of a round loaded in a gun, and means associated therewith for simultaneously firing said round when the fuse has 80 been set.

JAMES C. KARNES.
